UNITED STATES PATENT OFFICE.

ROBERT M. MERRIMAN, OF AKRON, OHIO.

DESIGN FOR A TIRE TREAD.

Application filed November 14, 1924. Serial No. 11,381. Term of patent 7 years.

To all whom it may concern:

Be it known that I, ROBERT M. MERRIMAN, a citizen of the United States of America, residing at Akron, in the county of Summit and State of Ohio, have invented a new, original, and ornamental Design for a Tire Tread, of which the following is a specification, reference being had to the accompanying drawing, forming a part hereof.

In the drawing:

Fig. 2 is a plan view of the same, and
Fig. 3 is a side view thereof.

I claim:

The ornamental design for a tire tread, as shown.
